LAMP BRACKET

Herman Heidt, Inglewood, Calif., assignor to S & M Lamp Co., Los Angeles, Calif., a corporation of California

Application October 10, 1949, Serial No. 5,416

Term of patent 7 years

(Cl. D48—4)

To all whom it may concern:

Be it known that I, Herman Heidt, a citizen of the United States, residing at Inglewood, county of Los Angeles, State of California, have invented a new, original, and ornamental Design for Lamp Bracket, of which the following is a specification, reference being had to the accompanying drawing, forming a part hereof, in which

Fig. 1 is a top plan view of a lamp bracket showing my new design;

Fig. 2 is a bottom plan view;

Fig. 3 is a rear elevation;

Fig. 4 is a side elevation;

Fig. 5 is a front elevation;

Fig. 6 is a vertical mid-section.

I claim:

The ornamental design for a lamp bracket, as shown.

HERMAN HEIDT.
